US0D1019666S

(12) **United States Design Patent** (10) Patent No.: **US D1,019,666 S**
(45) Date of Patent: ** Mar. 26, 2024

(54) **BUTTON FOR A COMPUTING INPUT DEVICE**

(71) Applicant: **Microsoft Corporation**, Redmond, WA (US)

(72) Inventors: **John Helmes**, Limburg (NL); **Aditha May Adams**, Seattle, WA (US); **Simon Cameron Dearsley**, Bellevue, WA (US); **Go Osaki**, Shenzhen (CN); **Hongshan Sun**, Shenzhen (CN)

(73) Assignee: **Microsoft Corporation**, Redmond, WA (US)

(**) Term: **15 Years**

(21) Appl. No.: **29/837,975**

(22) Filed: **May 10, 2022**

(51) LOC (14) Cl. **21-01**

(52) U.S. Cl.

USPC **D14/388**; D14/400; D21/333

CLAIM

The ornamental design for a button for a computing input device, as shown and described.

DESCRIPTION

FIG. 1 is a front perspective view of a split button for a computing input device showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets
